UNITED STATES PATENT OFFICE

102,251

DESIGN FOR A PLASTIC SHEET OR SIMILAR ARTICLE

William Bowker, Union, N. J., assignor to Cellu-
loid Corporation, a corporation of New Jersey

Application November 23, 1935, Serial No. 59,720

Term of patent 7 years

To all whom it may concern:

Be it known that I, William Bowker, a citizen of the United States, residing at Union, county of Union, State of New Jersey, have invented a new, original, and ornamental Design for a Plastic Sheet or Similar Article, of which the following is a specification, reference being had to the accompanying drawing, forming part thereof.

In the accompanying drawing:

The figure is a plan view of a plastic sheet or similar article showing my new design.

The thickness of the sheet or similar article is not an important part of the design. The characteristic feature of the ornamentation of the

sheet or similar article shown in the drawing comprises the arrangement of the alternating stripes of contrasting colors and the effect produced by having the lighter stripes themselves composed of square-like portions of contrasting appearance, some of which square-like portions (shown in shaded areas on the drawing) have pearl luster effects.

I claim:

The ornamental design for a plastic sheet or similar article, substantially as shown and described.

WILLIAM BOWKER.
